DESCRIPTION

FIG. 1 is a reduced perspective view of a cargo cage for a kayak tank well embodying the present invention;

FIG. 2 is a right side view of the cargo cage shown in FIG. 1;

FIG. 3 is a left side view of the cargo cage shown in FIG. 1;

FIG. 4 is a front view of the cargo cage shown in FIG. 1;

FIG. 5 is a rear view of the cargo cage shown in FIG. 1;

FIG. 6 is an enlarged bottom view of the cargo cage shown in FIG. 1;

FIG. 7 is an enlarged top view of the cargo cage shown in FIG. 1; and,

FIG. 8 is a reduced perspective view of the cargo cage shown in FIG. 1 positioned within the tank well of a kayak.

The structures depicted by broken lines in the figures are shown as environment or for illustrative purposes and form no part of the claimed design.
